ASSEMBLER CONTROL EQUIPMENT FOR
TYPE LINE CASTING MACHINES

John R. Brougher, Calvert, Tex.

Application January 10, 1949, Serial No. 69,993

3 Claims. (Cl. 199—32)

1

This invention relates to assembler control equipment for type line casting machines.

An object of the invention is to provide novel means for controlling the assembler, wherein the matrices are assembled by the operator without diversion from the copy or interference with the operation of the keys of the keyboard.

Another object of the invention is to provide, in a type line assembling machine, such as those known by the trade name of Linotype, or similar machine, an assembler elevating mechanism which, when released by the operator, will automatically elevate the assembler and return it to original, or set, position in readiness for the elevation of the succeeding line of matrices.

The invention is of such construction that the operator may devote his entire attention to the copy and the keyboard without, substantially, diverting his attention to the operation of the assembler.

The invention also includes what is hereinafter defined as a send-in safety device. This safety device is a matrices aligner which effectively aligns the matrices preparatory to the transfer of the matrix assembly in the usual and customary manner, common to type line assembling machines, to complete the casting process.

It is a further object of the invention to provide, in a machine of the character described, a send-in safety device for the purpose specified but which may be rendered inactive without detachment from the machine.

Other objects and advantages will be disclosed by the following specification which is illustrated by the accompanying drawings wherein:

Figure 1 is a fragmentary front elevation of a line casting machine such as those known by the trade names Linotype or Intertype illustrating the improvements which form the subject matter of the present invention.

Figure 2 is an enlarged elevational view of a send-in safety device.

Figure 3 is a sectional view thereof taken on the line 3—3 of Figure 2.

Figure 4 is an enlarged transverse sectional view taken on the line 4—4 of Figure 2.

Figure 5 is a plan view, partly in section of the assembler elevating mechanism.

Figure 6 is a cross sectional view thereof taken on the line 6—6 of Figure 5.

Figure 7 is a cross sectional view thereof taken on the line 7—7 of Figure 5.

Figure 8 is a fragmentary sectional view thereof taken on the line 8—8 of Figure 5, and

Figure 9 is an end view thereof viewed as indicated by the line 9—9 of Figure 5.

2

Referring now more particularly to the drawings wherein like numerals of reference designate similar parts in each of the figures, the numeral 1 designates the main frame of the assembler elevating mechanism which, in the present illustration, is in the form of a bar having the forward and rearward upturned ends 2, 3. The extremities of these upturned ends have the diagonal faces 4 and 5 which are pitched in opposite directions, the face 4 being pitched downwardly to the left and the face 5 being pitched downwardly to the right.

The frame 1 is provided with marginal notches 6, 6 to receive the bolts 7, 7 which upstand from a shelf-like projection of the main frame 8 of the type line assembling machine and said frame 1 is secured in position by suitable nuts 8a, 8a which are screwed onto the upstanding bolts 7.

The frame 1 supports a shaft 9 which is rotatable in bearings in the upstanding ends 2, 3, as shown in Figures 5 and 7.

On the shaft 9 are the ratchet wheels 10, 11, each having a single tooth as 12 and 13 pitched in opposite directions. The ratchet wheel 10 is loosely mounted on the shaft to rotate independently thereof but the ratchet wheel 11 is fixed to the shaft to rotate therewith. The ratchet wheel 10 is retained on the shaft by means of a suitable collar 14 which is suitably secured in place.

Fastened to the shaft 9, adjacent the upturned end 2 of the frame 1 there is a laterally extended arm 15 and pivoted to the outer end of said arm there is a lever 16 whose free end extends over the shaft 9 and is provided with an outwardly extended roller 17 which rides on the sloping face 4 and which is positioned to be engaged by ratchet tooth 12. The roller 17 is held in yielding contact with face 4 by means of a coil spring, or other tension member 16a which connects lever 16 to frame 1.

At the other end of shaft 9 there is a bar 18 which is provided with an oblong longitudinal slot 19 through which the shaft 9 extends and there is a lever 20 which is pivoted, at one end, to the bar 18 and which extends across the shaft 9 in adjacent relation with the ratchet wheel 11 and mounted on, and extending outwardly from, the lever 20 there is a roller 21 which rides on the sloping face 5 and which is engageable with the ratchet tooth 13.

The free end of the lever 20 is connected to the corresponding end of the bar 18 by means of a suitable coil spring, or other elastic tie member 55 22.

Attached to the shaft 9, intermediate its ends

there is an arm 23 which extends out laterally from said shaft, to the left, in the present illustration, and attached to the free end of said arm, at one end, there is a coil spring 24 whose other end extends upwardly and is attached to the main frame of the machine 8.

Pivots connected to the end of the bar 18, remote from the slot 19, there is a clamp arm 25 which is formed into a clamp 26 which is fitted around the hub 27 that is secured on a lever 28 of the main type line assembling machine. This lever 28 oscillates back and forth so as to move the bar 18 in the direction indicated by the arrow in Figure 7 when the line of assembled matrices is transferred toward the left in the front part of the main machine and which moves said bar 18 in the opposite direction when transfer at the front of the main machine returns to original, or starting, position; upon movement of the bar 18 to the right, as above explained, following the transfer of the line to the left at the front of the machine, the roller 21 drops behind the ratchet tooth 13 and when the bar 18 is moved in the opposite direction, upon return of the transfer in front of the machine, the roller 21 engages against said ratchet 13 and thus rotates the shaft 9, thus moving the arm 23 downwardly and placing the spring 24 under tension.

There is a U-shaped bracket 29 one end of which is fastened to the ratchet wheel 10 and whose other end is extended and secured to said extended end there is an arm 30 which is preferably arcuate and downwardly curved as shown in Figure 9.

There is a rod 31 pivotally connected, at its lower end, to the free end of the arm 30 and at its upper end to the lower end of the assembler 32 as shown in Figure 1. This rod 31 is provided with a turn buckle 33 for proper adjustments; this turn buckle 33 is adjusted so that when the assembler 32 reaches the required limit of its upward movement the roller 17 has moved upwardly along the sloping face 4 until it clears the ratchet tooth 12 thus releasing the ratchet wheel 10 permitting the bracket 29, arm 30 and attached assembler to drop back to original position by gravity. Ratchet wheel 10, bracket 29, arm 30 and rod 31 form an elevator.

There is a depending bracket 34 secured to a suitable part of the main machine, as shown in Figure 6, which is provided with a forwardly directed vertical flange 35 to which a trigger 36 is pivotally connected. The free end of this trigger works through a vertical slot 37 in the bracket 34 and when the assembler is in its lower position said trigger engages over the arm 30 to hold said arm in its lower position. The latch 36 is extended upwardly and turned forwardly, as shown in Figure 6, and terminates in an upstanding lever 38. This construction holds the latch by gravity, through slot 37 and in arm engaging position, as shown in Figure 6. But upon movement of the lever 38 rearwardly, that is in the direction indicated by the arrow in Figure 6, the latch will be released; however, when the assembler 32 drops down by gravity, as hereinabove indicated, the arm 30 will contact the downwardly and rearwardly tapered end 36a of the trigger and will move the trigger outwardly passing beneath it whereupon the trigger will engage above said arm and again latch it in its lower position, with the roller 17 behind the ratchet 12; the machine is then ready for again placing the spring 24 under tension upon movement of the bar 18 to the left thus causing the roller 21 to

engage the ratchet 13 to rotate the ratchet wheel 11 and shaft 9 to impart this tension to the spring 24.

Secured to the lower end of the bar 34 there is a guide 39 which extends upwardly and is spaced from the bar 34 thus forming a guideway in which the arm 30 moves.

As illustrated the assembler 32 is in its lower position to receive the line of matrices 40 in accordance with the operation of the keys of the keyboard, by the operator. In this position the arm 30 is latched in its lower position until a line of matrices has been completed. Upon completion of the line the operator merely moves lever 38 rearwardly, as indicated by the arrow in Figure 6. The operator can easily operate the lever 38 without diverting his mind from the copy or from the keyboard and, with an experienced operator, this action can take place substantially automatically on the part of the operator. The spring 24, being under tension, will thereupon rotate the shaft 9 in a clockwise direction thus elevating the free end of the arm 15 resulting in a corresponding movement of the lever 16 and roller 17, said roller operating against the tooth 12 to rotate the ratchet wheel 10 with the result that the arm 30 will be swung upwardly and, through the rod 31, will lift the assembler 32 while the roller 17 rides up along the face 4 and is elevated until said roller 17 is released by the tooth 12 whereupon the assembler 32 will descend to its original line-receiving position by gravity thus forcing the arm 30 downwardly into position underneath the latch 36, as shown in Figure 6, whereby the assembler will be latched in its lower position and meanwhile the bar 18 will have moved to the left with the roller 21 engaging the ratchet tooth 13 and partially rotating the ratchet wheel 11 and shaft 9 in an anti-clockwise direction to again place the spring 24 under tension and to carry the roller 17 back into position to engage behind the tooth 12 whereupon the machine will be in readiness to again lift the assembly upon completion of a line of matrices and upon operation of the lever 38.

Upon elevation of the assembler to the limit of its upward movement the line of matrices is transferred in the usual and customary manner common to Linotype or Intertype machines to complete the casting process.

It is very desirable that the matrices remain in substantially transverse alignment during, and particularly at the end of, the upward movement of the assembler. In machines now in common use the matrices often fail to seat properly when they are dropped into the assembler; also even though the matrices are properly seated in the assembler at the beginning of its upward movement it sometimes happens that some of the matrices move on upwardly out of alignment upon sudden stoppage of the assembler particularly if the assembler is sent up too swiftly. In either event if one or more of the matrices project above the level of the line of the matrices in the assembler the elevated matrices hang against the entrance of the receiving channel when the transfer carries the line of matrices to the left. This either stops the transfer and the operator must spend considerable time disengaging the hanging matrices and aligning them; or if the resistance is not sufficient to stop the transfer the out-of-line matrix is bent or marred and if it then goes through the casting cycle and is carried to the top of the machine through the distributor unit and dropped back into the top of

the magazine the damaged matrix or matrices will hang in the magazine thus causing an accumulation of matrices until the channel is filled and the distributor is stopped. Thereupon, the operator must spend considerable time removing all the matrices down to the damaged one which must be removed. This causes considerable loss of time as well as loss of matrices.

In order to assure the proper alignment of the matrices in the assembler at the termination of the upward movement of the assembler special equipment has been provided as shown in detail in Figures 2, 3 and 4 wherein the numeral 41 designates a supporting frame which is secured, at the proper elevation, to the type line assembling machine. This frame extends transversely of the machine and at its end adjacent the assembler track is the forwardly directed spaced lugs 42, 42a. There is a send-in safety bar 43 which is shown in plan view in Figure 3 and in front elevation in Figure 2. This bar has an integral hinge member 43a which fits between the lugs 42, 42a and is pivotally mounted by means of a suitable setscrew 44 passing through said lugs. This send-in bar 43 may be swung into active position into alignment with the frame 41 as shown in Figure 3 during the ordinary type-setting work; however, as it is pivoted on the setscrew 44 it may be swung around to the left into inactive position when mixed lines of black face and light face matrices are sent in for the reason that the black face portion of the line automatically rides higher in the assembler than the light face line and in such circumstances the send-in bar cannot be used.

It will be noted, particularly from an inspection of Figure 4, that the bar 43 is provided, on its under side, with a longitudinal groove 45 to conform to the shape of the adjacent ends of the matrices 40 and said bar is also adjusted to the machine so that when a line is sent up with the matrices in normal fully seated position there will be a slight clearance on both sides and at the top between the space-bands and the aligning bar 43 and the space-bands will not touch said bar as the line is transferred; however, if the matrices are elevated above the normal position they will come into contact, when the assembler is elevated, with the bar 43 and will be pushed back into their proper position so as not to hang at the entrance of the transfer channels.

Thus the operator is relieved of manually aligning the matrices in the assembler and mentally relieved from the danger which would otherwise be incidental to the operation of the machine in case the matrices are not properly aligned, to the end that the operator can concentrate his efforts on the copy and on the keyboard thus making the work of the operator much easier and increasing the volume and accuracy of his work. It is here noted that the send-in assembly disclosed in detail in Figures 2, 3 and 4 may be used either in conjunction with, or independently of, the assembler elevating

mechanism disclosed in detail in Figures 5 to 9 inclusive.

The drawings and description are illustrative merely and it is to be understood that the invention is not restricted to the precise form shown and described but the broad principle of the invention will be defined by the appended claims.

What I claim is:

1. In a type line casting machine, a vertically movable assembler adapted to receive and elevate a line of matrices, and a send-in safety bar above, and in vertical alignment with, the assembler and having a longitudinal groove in its underside shaped to receive the adjacent ends of matrices in the assembler said bar being engageable with matrices in the assembler which are elevated above normal position to restore the elevated matrices to normal position, upon termination of the upward movement of the assembler.
2. In a type line casting machine, a vertically movable assembler adapted to receive and elevate a line of matrices, and a send-in safety bar above, and in vertical alignment with, the assembler and having a longitudinal groove in its underside disposed to receive the adjacent ends of matrices in the assembler said bar being disposed to clear matrices which are in normal position in the assembler and to engage matrices which are elevated above normal position and restore the elevated matrices to normal position, upon termination of the upward movement of the assembler, said bar being pivoted so that it may be swung into inactive position.
3. In a type line casting machine, a send-in safety bar which is mounted to be swung horizontally into an active position in vertical alignment with, and above, the assembler of the machine and which may be swung into an inactive position out of such alignment said bar having a longitudinal groove adapted to guidingly receive the adjacent ends of matrices in the assembler when the bar is in said active position and to engage matrices in the assembler which are elevated above normal position therein and restore the elevated matrices to normal position.

JOHN R. BROUGHER.
